UNITED STATES PATENT OFFICE.

OSCAR L. MERROW AND ALBERT E. SANBORN, OF LACONIA, NEW HAMPSHIRE, ASSIGNEES OF ONE-HALF TO DENNIS O'SHEA AND JOHN O'SHEA, JR., BOTH OF SAME PLACE.

SPLICING-THREAD ATTACHMENT FOR KNITTING-MACHINES.

SPECIFICATION forming part of Letters Patent No. 434,156, dated August 12, 1890.

Application filed January 11, 1890. Serial No. 336,619. (No model.)

To all whom it may concern:

Be it known that we, OSCAR L. MERROW and ALBERT E. SANBORN, of Laconia, in the county of Belknap and State of New Hampshire, have invented certain new and useful Improvements in Splicing-Thread Attachments for Knitting-Machines, of which the following is a specification.

Our invention has for its object the provision of means whereby an additional or "thickening" thread may be introduced to a portion of the needles of the circle in a circular-knitting machine, so as to strengthen or thicken the circular web at desired points— as, for instance, at the knees and heels and toes of stockings.

Our invention consists of means for intermittently feeding a thickening-yarn to the needles of a knitting-machine, which means comprise a rotary hub having a projection in which there is arranged a yarn-carrying spindle so constructed as that it may be moved longitudinally in the projection, whereby in bringing the thickening-yarn into position to be fed to the needles and withdrawing it from action, it may be moved vertically by rotating the hub and horizontally by a longitudinal movement of the spindle.

By our improvements, hereinafter described and claimed, we are enabled to introduce and withdraw the thickening-yarn with certainty at each operation on the same wales of the knitted fabric, and in such manner as to leave but short projecting ends at the points of introduction and withdrawal.

Reference is to be had to the annexed drawings, and the letters and figures of reference marked thereon, forming a part of this specification, the same letters and figures designating the same parts or features, as the case may be, wherever they occur.

In the said drawings, Figure 1 is a top view of a circular-rib-knitting machine equipped with my improvements. Fig. 2 is a perspective view of a portion of the same. Fig. 3 is a front elevation. Fig. 4 is a sectional detail, looking, as it were, from the center of the cylinder, showing the yarn-carrier for introducing the thickening-yarn as in action

and about to be thrown out of operation. 50 Fig. 5 is a view similar to Fig. 4, showing the same yarn-carrier as out of operation and the end of the yarn as about to be severed by the shears. Fig. 6 is a perspective detail, on an enlarged scale, showing the yarn-carrier for the thickening-yarn and some of its adjuncts. 55

In the drawings, *a* designates the needle-cylinder; *b*, the needles arranged to be reciprocated in grooves in the cylinder; *c*, the cam-cylinder; *d*, the dial-plate; *e*, the dial-needles; *f*, the cam-plate provided with means for operating the dial-needles; *g*, the yoke connecting the cam-cylinder *c* with the cam-plate *f*, and *h*, the yarn-guide for feeding the regular knitting-yarn to the needles. These parts are constructed and arranged in a common way, so that with them and other well-known adjuncts a circular ribbed web may be knit, though, so far as our invention is concerned, 70 the machine represented might be considered as one organized to produce a plain circular web—*i. e.*, as a machine without ribbing appliances.

The yarn-carrier for introducing the thickening-yarn consists of a hub *h*, connected with a spindle *i*, journaled at its outer end in the upper end of a bracket *j*, connected with the cam-cylinder, and at its inner end the said spindle is journaled in a block *j*², secured to 80 the cam-plate *f*, or, for that matter, it might be in the cam-plate itself. The hub *h* is provided with a projecting part *k*, in which the yarn-carrying spindle *l* is arranged so as to be moved longitudinally.

The spindle *l* and the projection *k* supporting the same are provided with thread or yarn guide holes *l*¹ *l*², to properly guide the thickening-yarn to the needles and severing and holding devices.

m is a spring connected with the spindle *l* and bearing against the projection *k* of hub *h* in such manner as to hold the rear end of the said yarn-carrying spindle normally against what may be termed a "cam-bracket" 95 *n*, which is connected with the cam-cylinder *c* and is curved inward at its upper end or top, as most clearly shown in Fig. 6, so that

when the yarn-carrier for the thickening-yarn is thrown out of action by being raised the spindle will at the same time be moved inward toward the center of the cam-plate, carrying the thickening-yarn into the notch or yarn-holder j' , formed between the block j^2 and the cam-plate f . The outer end of the spindle i is provided with a hub o , having radially-projecting pins p and q , arranged at different points circumferentially upon the said hub o .

r is an arm arranged on a bracket s , which arm is so placed that in the rotation of the cam-cylinder the pin p may come in contact therewith, with the result of partially rotating the spindle i and its attached hub h .

t designates a bracket secured to the cam-plate f , which bracket supports the yarn-severing shears consisting of a fixed blade u and a pivoted blade v , the latter having a rearwardly-extending arm w , which is held by means of a spring x' , to normally bear against the upwardly-extending portion of an angular lever x , pivoted on a bracket y , connected with the cam-cylinder c . The said lever x is provided with a spring x^2 , which tends to hold it in contact with the arm w of the pivoted blade of the shears, the two springs mentioned operating to keep the parts so placed as to normally hold the shears open.

z designates a pin projecting up from a bracket a' , connected with a fixed part of the machine, which pin is so placed that in the rotation of the cam-cylinder the outer end of lever x may be brought in contact therewith and be moved upon its fulcrum so as to operate blade v and close the shears, the latter being opened after pin z is passed by means of the springs before mentioned.

b' designates a bracket connected with a fixed part of the machine, which bracket supports a radially-movable slide c' , adapted to be moved out into the path of travel of pin q on hub o , and so partially rotate said hub and spindle i in a direction contrary to that in which they were rotated by the operation of arm r on pin p . A spring d' holds the slide c' normally back out of the path of travel of pin q .

e' is a longitudinally-movable rod supported in bracket b' , and provided with an inclined cam-piece f' , which cam-piece is adapted to operate against the outer end of the slide c' , so that by raising the rod e' the cam-piece f' will effect the moving of the slide inward to the dotted-line position, Fig. 1, the said slide being moved back by the spring connected therewith, as before described. The rod e' may be arranged to rest on a pattern-chain g' on a sprocket-wheel h' , Fig. 1, a step-by-step movement being imparted to said sprocket-wheel as the cam-cylinder is rotated, and the swells i' on the chain g' passing under the end of the said rod serving to raise the latter and hold it in raised position as long as needed. The bracket b' and its adjuncts may be connected with the machine at a point

opposite that at which the arm r is connected therewith.

In the knitting of a tubular web, when a point shall have been reached at which it is desired to introduce a thickening-thread into the web, rod e' will be raised and cam-piece f' on the said rod acting on the end of slide c' will move the latter forward to the dotted-line position, Fig. 1, when in the rotation of the cam-cylinder the pin q will come in contact with the slide, partially rotating hub o and spindle i , bringing the yarn-carrier from the position in which it is represented in Fig. 80 to that in which it is represented in Fig. 4, and so that the thickening-thread z' passing through yarn-carrying spindle l will be fed to the needles. This operation will continue until the hub o reaches the arm r , when pin p 85 coming in contact with the said arm will partially rotate the hub o and its spindle in a direction opposite to that in which it was previously moved, bringing the yarn-carrier into the position in which it is shown in Fig. 5. 90

In the last-mentioned operation as the projection h of hub h is raised, the spindle l in said projection, acted upon by the cam-bracket n , will be moved inward as well as upward, carrying the yarn between and to the rearward of needles 2 3, and drawing the end into the holder j' , which consists of a simple notch formed between the collar or block j^2 and the cam-plate f , to which the said block is secured and into which block or collar the inner end of spindle i passes. The said notch j' may be formed by filing away a portion of the inner face of the block j^2 , so that the yarn when drawn into the notch, as it will be when thrown out of action and moved inward toward the center of the cam-plate, as is shown most clearly in Fig. 6, will become to a degree wedged or held in the said notch. Other suitable known means may, however, be provided for holding the end of the yarn. The rotation of the cam-cylinder continuing the portion of the yarn z' between the holder j' and the needles will be drawn into the shears, immediately upon which stud or pin z will strike the outer end of lever x , closing the 105 shears and severing the yarn. The end of the yarn z' coming from the bobbin will be retained in the holder j' until pin q again comes in contact with the slide c' , when the before-described operations will take place. 110 When the yarn-carrier is thrown out of operation, the yarn-guide k' extending up from the carrier will operate to draw off a little yarn from the bobbin before the said yarn is severed by the shears, so that when the carrier is brought into operation slack sufficient will be payed out to insure the retention of the end in the holder j' until the yarn is drawn between and is caught by the needles. 115 At each operation the yarn will be drawn between the same pairs of needles, so that the beginning and ending of the knitting-in of the thickening-thread will always be on the same wales. 120

By this invention a simple and entirely efficient means is provided for introducing a thickening-yarn, and a means that is most certain in its operation.

5 It is obvious that changes may be made in the form and arrangement of parts comprising our improvements without departing from the nature or spirit of the invention.

What we claim is—

10 1. As a means for intermittently feeding a thickening-yarn to the needles of a knitting-machine, the rotary hub h and its projection k , and the yarn-carrying spindle in the said projection and longitudinally movable there-

15 in, and means for actuating the hub and spindle, as set forth.

2. As a means for intermittently feeding a thickening-yarn to the needles of a knitting-machine, the rotary hub h and its projection

20 k , the yarn-carrying spindle in the said projection and longitudinally movable therein, a spring to move said spindle in one direc-

25 tion and a cam-bracket to move it in the opposite direction, means for actuating the rotary hub, and a cutter and holder for the yarn, as

set forth.

3. The combination, with the needle-cylinder, needles, and rotary cam-cylinder, of the rotary hub provided with radially-pro-

30 jecting pins and having the projection k , the yarn-carrying spindle in the said projection and longitudinally movable therein, a spring

to move said spindle in one direction, a cam-bracket to move it in the opposite direction, a cutter and holder for the yarn, and stationary 35 stops with which the radial pins may come in contact, as set forth.

4. As a means for cutting or severing a yarn thrown out of action, the combination, with the needles, needle-cylinder, cam-cylinder, 40 dial, and dial cam-plate, of the bracket t , the shear-blades thereon, one of said blades being pivoted and provided with extended arm w , pivoted lever x , springs connected with said arm w and lever x , and stationary pin z , as 45 set forth.

5. The combination, with the needle-cylinder, needles, cam-cylinder, and regular yarn-guide, of an additional yarn guide and carrier consisting of a rotary hub h and its pro- 50 jection k , and the yarn-carrying spindle therein, means for actuating the rotary hub and yarn-carrying spindle, and a holder and cutter for the yarn, as set forth.

In testimony whereof we have signed our 55 names to this specification, in the presence of two subscribing witnesses, this 1st day of January, A. D. 1890.
